McMILLAN BOOK COMPANY, OF SYRACUSE, NEW YORK, A CORPORATION OF NEW
YORK.

FLEXIBLE-POST BINDER.

Application filed December 27, 1927. Serial No. 242,744.

This invention relates to a new and improved loose leaf binder of the type commonly called a flexible post binder.

In devices of this description it is desirable to have a binder in which the available length of posts can be varied. That is to say, a binder in which the amount of available posts between the covers can be increased from time to time as new sheets are inserted.

We are aware that binders, to accomplish this specific purpose, have already been made but in every binder of this type heretofore known it has been difficult, if not impossible, to insert new sheets or to remove sheets without first increasing the length of the available posts. The increasing of the length of the posts is always done by the use of some sort of a key device and in consequence considerable amount of work has to be done before an additional sheet can be inserted, or a sheet removed.

The main object of our invention is to design a structure which will have the advantage of posts which can be lengthened at will, but which will also have the advantage of temporarily permitting the lengthening of the posts for insertion of additional leaves without the necessity of operating the regular post extending device.

Other objects and advantages relate to the size, shape and arrangement of parts as will more fully appear from the following description taken in connection with the accompanying drawings in which:

Figure 1 is a perspective view, partially broken away, of our device as assembled in a book.

Figure 2 is a section on line 2—2 of Figure 5.

Figure 3 is a section on line 3—3 of Figure 5.

Figure 4 is a section on line 4—4 of Figure 5.

Figure 5 is a section on line 5—5 of Figure 1.

Figure 6 is a section on line 6—6 of Figure 5.

Our device consists of an upper housing —1— and a lower housing —2— hingedly connected to upper and lower covers —3— and —4— respectively between which are confined sheets —5—.

The upper housing —1— consists of a bottom plate —6— U-shaped in cross section and having at either end holes 7—7 which holes carry on their inner edges depending curved guide pieces 8—8. One edge bottom plate —6— carries a plurality, in this case four, projecting eye portions —9— between which are received eye portions —10— of cover —3—. A pindle —11— is passed through eye portions —9— and —10— to hold the same together and to create what is in effect a piano hinge. A cover —12— of the same cross section as bottom plate —6— is fitted on bottom plate —6— to form a hollow approximately rectangular casing. An end plug —13— is positioned in one end of the casing formed by cover —12— and bottom plate —6— and carries on its inner face a socket —15— for a purpose hereinafter to be described. Another end plug —14— is positioned in the opposite end of the casing and is formed with a cylindrical hole —16— for a purpose hereinafter to be described. A bearing plate —17— is positioned against the inner face of end plug —13— and a corresponding bearing plate —18— is positioned against the inner face of end plug —14—. A rod —19— extends the length of casing formed by cover —12— and bottom plate —6— adjacent to one side thereof and having one end journaled in socket —17— and the other end journaled in bearing plate —18—. The rod —19— is sufficiently long to extend into the hole —16— and the part —20— of rod —19— which extends into hole —16— is square in cross section for engagement with a key or crank (not shown). One end of rod —19— carries a right hand thread —21— and the opposite end of rod —19— carries a left hand thread —22—. Locking nuts —23— and —24— are carried on the threaded ends —21— and —22— respectively of rod —19— and are of such a shape that the housing —1— will prevent their rotary movement when the rod —19— is rotated. A guide plate —25— is positioned in housing —1— at approximately the center point thereof, and a guide rod —26— extends through guide plate —25— and bears on bearing plates —17— and —18—. Guide rod —26— is positioned parallel to rod —19— and adjacent the opposite side of housing —1—.

—1—. Flexible posts —27— and —28— are inserted into housing —1— through holes —7—.

These flexible posts —27— and —28— are similar in construction and are preferably made of tongue and groove links —29— held together by pintles —30—. The inner ends of flexible posts —27— and —28— carry guide links —31— and —32— respectively, 10 said guide links being movably mounted on guide rod —26—. Guide rod —26— also carries a spring retaining collar —33— abutting against guide plate —17— and a slidable spring retaining collar —33'— normally 15 abutting against guide link —31—. A spring —34— is interposed between the spring retaining collar —33— and the spring retaining collar —33'—, said spring —34— encircling guide rod —26—. Similarly a spring retaining collar —35— is carried on guide rod —26— abutting against bearing plate —18—, and a similar spring retaining collar —36— is carried on guide rod —26— and is slidable thereon and normally abuts against guide 20 link —32—. Similarly a spring —37— encircles guide rod —26— and bears against spring retaining collars —35— and —36—.

Lock nuts —23— and —24— extend downwardly through holes 7—7 in bottom plate —6— and have curved faces adjacent flexible posts —27— and —28— respectively. The proportions of lock nuts —23— and —24— are such that when they are moved inwardly by the rotation of rod —9— they will be forced against flexible posts —27— and —28— to hold the same locked in position. The socket —17— is of a sufficient depth with relation to the length of rod —19— that a limited longitudinal movement of rod —19— is permitted so that in all cases lock nuts —23— and —24— will simultaneously contact and lock flexible posts —27— and —28—. When the lock nuts —23— and —24— are moved outwardly they will be stopped by the outside edges of holes 7—7 in a position to act as guides for flexible posts —27— and —28— when they are moved in and out through holes 7—7. A protecting plate —37— having spaced holes —38— and —39— for permitting the passage of flexible posts —27— and —28— is positioned on the underside of bottom plate —6— and is formed so as to register with the bottom edges of guides 8—8 and to act as a protecting plate for leaves —5—. Protecting plate —37—, bottom plate —6—, end plug —13— and cover —12— are fastened together by means of rivets —40—. Similarly at the other end 45 protecting plate —37—, bottom plate —6—, end plug —14— and cover —12— are fastened together by means of rivets —41—.

The lower housing —2— is formed with an upper plate —42— which is U-shaped in cross section and which carries spaced holes —43— and —44— positioned so as to register

with holes 7—7 in housing —1—. Upwardly extending curved guides —45— and —46— are positioned on the inner edges of holes —43— and —44— respectively. One edge of top plate —42— carries a plurality, in 70 this case four, of projecting eye portions between which are received registering eye portions of cover —4— which eye portions are held together to form a hinge by a pintle. The hinge construction for housing —2— 75 is not shown in the drawing except in sectional views shown in Figures 3 and 4 but is similar in all respects to the hinge construction of housing —1— previously described. A bottom plate —47— similar in cross section to top plate —42— is fitted on top of plate —42— to form a hollow approximately rectangular casing. Upwardly curving guide plates —68— and —69— are secured in bottom plate —47— and are so positioned as to direct the movement of flexible posts —27— and —28— through holes —43— and —44— respectively when flexible posts —27— and —28— are assembled in housing —2— as hereinafter described. An end plug —48— is positioned in the end of the casing formed by top plate —42— and bottom plate —47— and carries on its inner face a socket —49— for a purpose hereinafter described. A bearing plate —50— is positioned adjacent the inner face of end plug —48—. Another end plug —51— is positioned in the opposite end of the casing formed by top plate —42— and bottom plate —47— and is provided with a cylindrical 100 hole —52— for a purpose hereinafter described. A bearing plate —53— is positioned adjacent the inner face of end plug —51—. A guide plate —54— is positioned in the casing formed by top plate —42— and bottom plate —47— at approximately the center point thereof. A rod —55—, carrying on one end a right hand thread —56— and on the opposite end a left hand thread —57—, is positioned adjacent one longitudinal side of the casing formed by top plate —42— and bottom plate —47— and has one end journaled in bearing plate —50— and extends therethrough into socket —49—. The other end of rod —55— is journaled in bearing plate —53— and has an extension —58—, square in cross section, extending into cylindrical hole —52—. The square end —58— is designed to receive a key or crank (not shown) by which rod —55— is rotated. Nuts —59— and —60— are threaded on threads —57— and —56— respectively. The opposite ends of flexible posts —27— and —28— heretofore described are inserted through holes —44— and —45— and are connected by links —61— and —62— to nuts —60— and —59— respectively. A protecting plate —63— having spaced holes —64— and —65— registering with holes —43— and —44— respectively is positioned on the upper 130

side of top plate —42— and is of such a form and shape as to have its upper surface adjacent the upper edges of guides —45— and —46—. Protecting plate —63—, top plate —42—, end plug —48— and bottom plate —47— are secured together by rivets —66—. Similarly protecting plate —63—, top plate —42—, end plug —51— and bottom plate —47— are secured together by 10 rivets —67—.

Operation.

When rod —55— is rotated in the proper direction to carry nuts —59— and —60— 15 to the center of housing —2— a considerable portion of flexible posts —27— and —28— will be drawn and held inside of housing —2—. When it is desired to increase the available length of flexible posts —27— and 20 —28— between housings —1— and —2—, rod —55— may be rotated to the extent desired thereby moving nuts —59— and —60— towards the ends of housing —2— and forcing flexible posts —27— and —28— out of 25 the housing.

The action of springs —34— and —37— will normally hold guide links —31— and —32— in the center of housing —1— thereby retaining a considerable portion of flexible 30 posts —27— and —28— in the housing —21—. When it is desired to insert or withdraw sheets from between the housings —1— and —2—, these housings may be easily separated by drawing a portion of flexible posts —27— 35 and —28— out of the housing —1— against the action of springs —34— and —37—. When the sheet has been inserted or withdrawn the housings may be released and are immediately returned to their former position 40 under action of springs —34— and —37—. If it is desired to lock the book so that this just described operation can not take place, the screw —19— is rotated in the proper direction to carry nuts —23— and —24— 45 inwardly against flexible posts —27— and —28— which will prevent any movement of these posts.

It will be understood that this desirable result of having a flexible post binder so constructed that one end of each post is normally held in position by the action of a spring can be accomplished in ways other than by the specific construction just described. For although we have shown and described a specific structure and form of part as illustrative of an embodiment of our invention, we do not desire to restrict ourselves to the exact shape, form or relation of parts as various changes may be made within the scope of the appended claims.

What we claim is:

1. In a device of the class described, a pair of hollow clamping members, opposed apertures in said clamping members, a flexible post extending through each pair of opposed 65

apertures and having one end enclosed in one of the said clamping members and the other end enclosed in the other clamping member, a guide rod in one of said clamping members adjacent the enclosed ends of the flexible 70 posts, a guide link secured to the end of each of said flexible posts and being slidably mounted on said guide rod, and a spring interposed between each of said guide links and the adjacent end of said clamping member 75 whereby said flexible posts are yieldingly retained inside said clamping member.

2. In a device of the class described, a pair of hollow clamping members, opposed apertures in said clamping members, flexible post 80 extending through each pair of opposed apertures and having one end enclosed in one of the said clamping members and the other end enclosed in the other clamping member, a guide rod in one of said clamping members 85 adjacent the enclosed ends of the flexible posts, a guide link secured to the end of each of said flexible posts and being slidably mounted on said guide rod, a spring interposed between each of said guide links and the adjacent ends of said clamping member 90 whereby said flexible posts are yieldingly retained inside said clamping member, movable means adjacent each of said posts and means for moving such movable means to and from said posts whereby in one position said movable means will lock said posts against movement and in another position will function as guides for the movement of the posts through the apertures in said clamping member. 95

3. In a device of the class described, a pair of hollow clamping members, opposed apertures in said clamping members, flexible post 100 extending through each pair of opposed apertures and having one end enclosed in one of the said clamping members and the other end enclosed in the other clamping member, a guide rod in one of said clamping members adjacent the enclosed ends of the flexible 105 posts, a guide link secured to the end of each of said flexible posts and being slidably mounted on said guide rod, a coiled spring encircling said guide rod and being interposed between each of said guide links and the adjacent end of said clamping member whereby 110 said flexible posts are yieldingly retained inside said clamping member, movable means adjacent each of said posts and means for moving such movable means to and from said posts whereby in one position said movable means will lock said posts against movement and in another position will function as guides for the movement of the posts through the apertures in said clamping member. 115

4. In a device of the class described, a pair of hollow clamping members, opposed apertures in said clamping members, a flexible post extending through each pair of opposed 120 apertures and having one end enclosed in one 125

of the said clamping members and the other end enclosed in the other clamping member, a guide rod in one of said clamping members adjacent the enclosed ends of the flexible posts, a guide link secured to the end of each of said flexible posts and being slidably mounted on said guide rod, and spring means

for yieldingly retaining the flexible posts inside said clamping member.

In witness whereof we have hereunto set our hands this 7th day of December, 1927.

JOHN L. McMILLAN,
PAUL O. UNGER.
